CLAIM

The ornamental design for a mirror with over-the-door hanging system, as shown and described.

DESCRIPTION

FIG. 1 is a front elevational view of a mirror with over-the-door hanging system showing my novel design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a rear perspective view thereof; and,

FIG. 8 is a rear perspective view thereof where the hanger is in the extended position.

The broken lines in the drawings illustrate portions of the mirror with over-the-door hanging system that form no part of the claimed design.
